UNITED STATES PATENT OFFICE

EUGENE L. MESSLER, OF PITTSBURGH, PENNSYLVANIA

HOT TOP

Application filed February 27, 1930. Serial No. 431,828.

This invention relates to a hot top for ingot molds.

Problems have always been presented by the manufacturer, shipment and use of large refractory hot tops for ingot molds of relatively large size. It has been a practical impossibility to manufacture large hot tops either by extrusion or pressing as an integral structure, and even though they might be made experimentally by the laborious operation of molding, their size and weight combined with their fragility renders shipment and general handling of such large integral hot tops a commercial impracticability. When these large hot tops are made in sections for assembly at the time of use, the sections which comprise the corners of an assembled hot top must likewise be molded by hand, and these sections are difficult to pack and to ship without breakage, due to their angular contour and the inherent fragility of the material.

One object of my invention is to provide a sectional structure for refractory hot tops of large size in which all the corner sections of a hot top are initially formed as an integral structure, thus permitting them to be pressed, as in the modified sagger press disclosed in patent to Austin L. Moore No. 1,698,603, issued January 8th, 1929, and to be shipped as an integral structure, thus facilitating packing and reducing breakage.

Another object of the invention is to so form this integral structure constituting the corner pieces of an assembled hot top, and the intermediate or side members to be assembled therewith, that when the integral structure is divided to provide corner pieces these corner pieces neatly interlock with the intermediate or side sections and may be readily bound therewith to provide a hot top of relatively great size.

Still another object of the invention is to so construct the end and side members, that the large refractory hot top formed from them may have its parts so bound together as to permit the structure as a whole to be carried by a crane for positioning upon the ingot mold with which it is associated.

In the accompanying drawings Figure I is an inverted view of the integral pressed struc-

ture constituting when divided the corner pieces of the large hot top, showing the same partly in elevation and partly in vertical section; Fig. II is a bottom plan view thereof; Fig. III is a front elevation to smaller scale 55 of one of the integral or side pieces of the hot top, and Figs. IIIa and IIIb are respectively a side elevation and a top plan view thereof; Fig. IV is a top plan view of the several hot top portions assembled and ready to 60 be formed together to form a complete hot top (made by the assembly of the corner and side pieces); Fig. V is a side elevation of the assembled hot top, showing the same in position on an ingot mold; Fig. VI is a vertical 65 sectional view through a modified integral pressed structure constituting the corner members of the hot top; Fig. VII is a top plan view of a complete hot top constructed 70 by the division of the integral pressed structure shown in Fig. VI; and Fig. VIII is a cross sectional view through this complete hot top to still smaller scale, taken on the line 75 VII-VIII of Fig. VII.

In the drawings the reference numeral 1 designates generally the integral pressed refractory structure of the form shown in Figs. I and II of the drawings. This structure comprises an integral body member 2, which 80 has integral therewith a seating flange 3 for projection into an ingot mold and a shoulder 4 adjacent the mid section of the structure. This refractory corner piece structure is in effect a complete hot top of a size smaller 85 than that desired, and as such may be readily pressed in the modified sagger press above noted. It may also be packed and shipped, still as an integral structure.

Extending longitudinally of the structure 90 are four spaced and longitudinally extending slots 5, to provide interlocking shoulders for connection with the intermediate or side pieces of a complete hot top. Extending inwardly from the outer surface of the structure, intermediate each of the notches 5, is an indentation or groove 6. When the pressed structure is to be divided to provide four corner pieces, it is broken at the grooves. Each piece thus formed, as shown in Fig. IV of 100

the drawings, has a notch 7 lying at its ends and inwardly of the hot top structure.

As shown in Figs. IIIa and IIIb, each intermediate piece comprises a slab 8 having thereon a shoulder 9 to match with the shoulders 4 of the corner pieces, and is cut away to form flanges 10 arranged to match with the notches 7 of the corner pieces.

When the side and corner pieces have been assembled into a hot top structure they may be bound together by means of a metallic strap 11, the upturned ends 12 of which are interconnected by means of a bolt, or the like, 13. Desirably the strap 11 is provided with eyelets 14, to facilitate lifting and positioning of the hot top as a whole. It is noted that the strap 11 lies against the continuous shoulder formed by the shoulders 4 on the corner members and shoulder pieces 9 on the side members, so that it may not slip upwardly from the hot top. This permits the hot top to be lifted by the assembling strap 11. If desired an additional strap (not shown) may be applied in a lower region of the hot top for binding the pieces together adjacent the ingot mold.

The modified structure shown in Figs. VI to VIII inclusive of the drawings, is generally similar to that shown in the preceding figures, but is so arranged that the several pieces constituting the hot top interlock to prevent their relative vertical displacement. In this form the corner-piece structure designated generally by the reference numeral 16 has locking notches 17 which terminate at 18, adjacent but short of the upper end of the hot top. Longitudinally extending grooves 19 for division of the structure into corner pieces are provided in the region of the notches 17, similarly to those shown in Figs. I and II of the drawings. The side pieces 20 also have their locking flanges 21 terminating at 22, a distance from the upper end of these pieces equal to that lying between the termination 18 of notches 17 and the upper end of the corner-piece structure. This specialized interlocking binds the parts vertically, so that no shoulder is required, and the straps 23 may merely be tightened around the assembled hot top to prevent relative lateral displacement of the pieces.

It is to be understood that the hot top structure described herein is useful with large hot tops which present the problems previously described, and is not at present an economical arrangement with small hot tops, which may be conveniently made as integral structures. It does solve manufacturing and shipping problems with respect to the large size hot tops, in that it permits the corner pieces to be pressed rather than molded, and in that the corner pieces are, as manufactured, in suitable condition for shipment. Further, the special binding or interlocking of corner and side pieces permits a hot top structure

formed by the assembly of these pieces to be lifted and positioned on an ingot mold.

What I claim is:

1. For use in a multiple-piece hot top assembly, corner pieces for a complete hot top pressed as an integral structure, vertically extending shoulder-forming notches inset in the wall depth of the structure, and vertically extending lines of weakness in the structure opposed to said notches in the wall of the structure and extending parallel to and intermediate the edges of said notches, whereby breakage of the body along the lines of weakness provides vertically extending shoulders in each of the pieces. 80

2. For use in a multiple-piece hot top assembly, corner pieces for a complete hot top pressed as an integral structure, vertically extending shoulder-forming notches inset in the wall depth of the structure and terminating short of the upper end thereof, and vertically extending lines of weakness opposed to said notches in the wall of the structure and extending parallel to and intermediate the edges of said notches, whereby breakage of the wall along the lines of weakness provides vertically extending shoulders in each of the pieces terminating in horizontally disposed shoulders in the pieces. 95

3. For use in a multiple-piece hot top assembly, corner pieces for a complete hot top pressed as an integral structure, vertically extending shoulder-forming notches inset in the body depth of the structure from the interior surface thereof, and lines of weakness formed exteriorly of said structure and opposed to said notches in the wall of the structure and extending parallel to and intermediate the edges of said notches, whereby breakage of the wall along the lines of weakness provides vertically extending shoulders in each of the pieces lying inwardly with reference to the initial structure. 100

4. For use in a multiple-piece hot top assembly, corner pieces for a complete hot top pressed as an integral structure, vertically extending shoulder-forming notches inset in the wall depth of the structure from the interior surface thereof, two horizontal shoulders inset from the exterior surface of the wall and extending around the structure to provide seating and lifting ledges in use of the parts, and vertical lines of scoring opposed to said notches in the wall of the structure and extending parallel to and intermediate the edges of said notches, said lines of weakness in depth including said shoulders and a material portion of the remaining wall depth. 115

5. For use in a multiple-piece hot top assembly, corner pieces for a complete hot top pressed as an integral structure, vertically extending shoulder-forming notches inset in the body depth of the structure from the interior surface thereof and terminating short 130

of the upper end thereof, and vertically extending lines of weakness opposed to said notches in the wall of the structure and extending parallel to and intermediate the edges 5 of said notches, whereby breakage of the wall along the lines of weakness provides vertically extending shoulders terminating in horizontally disposed shoulders in each of the pieces lying inwardly with reference to 10 the initial structure.

6. A multiple-piece hot top assembly comprising corner pieces having therein notches extending vertically and terminating short of one end of the piece for interlocking with intermediate pieces in the assembly, and intermediate pieces having along their edges vertically extending flanges terminating short of one end of the piece and interlocking in 15 the assembly with the shoulders on the corner pieces.

7. A multiple-piece hot top assembly comprising corner pieces having therein interiorly disposed notches extending vertically and terminating short of one end of the piece for 20 interlocking with intermediate pieces in the assembly, and intermediate pieces having along their edges interiorly disposed and vertically extending flanges terminating short of one end of the piece and interlocking in 25 the assembly with the shoulders on the corner pieces.

In testimony whereof I have hereunto set
my hand.

EUGENE L. MESSLER.
